(57) **CLAIM**

The ornamental design for a rotary tool, as shown and described.

DESCRIPTION

FIG. 1 is a perspective view of a rotary tool showing our new design.

FIG. 2 is a left side elevational view of the rotary tool of FIG. 1;

FIG. 3 is a right side elevational view of the rotary tool of FIG. 1;

FIG. 4 is a top plan view of the rotary tool of FIG. 1;

FIG. 5 is a bottom plan view of the rotary tool of FIG. 1;
 FIG. 6 is a front elevational view of the rotary tool of FIG. 1; and,

FIG. 7 is a rear elevational view of the rotary tool of FIG. 1.

The broken lines shown in the drawings illustrate portions of the rotary tool that form no part of the claimed design.
